UNITED STATES PATENT OFFICE.

ERNEST R. SWANSON, OF CRANSTON, RHODE ISLAND, ASSIGNOR TO UNIVERSAL WINDING COMPANY, OF BOSTON, MASSACHUSETTS, A CORPORATION OF MASSACHUSETTS.

SLUB CATCHER OR YARN CLEANER.

Application filed March 19, 1927. Serial No. 176,702.

This invention relates to improvements in slub-catchers or yarn-cleaners for removing slubs, bunches, motes or other foreign matter from thread or yarn during the process of winding or otherwise transferring the material.

One object of the invention is to provide a device of the type specified having a slot or opening through which the yarn draws with means for securing a precise, accurate adjustment in the width of the slot in accordance with different sizes or thicknesses of yarn to be operated upon.

Another object of the invention is to provide an adjusting means for the slub-catcher which is operative only through the use of a special key or wrench so as to prevent unauthorized tampering with or change in the adjustment of the device after it has once been set.

Another object of the invention is to provide a device of the type specified having means for maintaining the yarn slot or opening of uniform width under all conditions of adjustment so that it will act with maximum efficiency in whatever position the yarn or thread draws therethrough.

Another object of the invention is to provide a device of the type specified which is simple in construction, economical to manufacture, and proof against derangement or getting out of order.

Further objects of the improvement are set forth in the following specification which describes a preferred form of construction of the invention as illustrated in the accompanying drawings. In the drawings:

Fig. 1 is a side elevation of a portion of a winding machine showing my improved slub-catcher or yarn-cleaner applied to use therewith;

Fig. 2 is a plan view showing the essential elements of the winding machine and its tension-device and illustrating my improved slub-catcher assembled therewith;

Fig. 3 is a front elevation of the improved slub-catcher or yarn-cleaner;

Fig. 4 is a cross-sectional plan view of the same taken on the line 4—4 of Fig. 3; and

Fig. 5 is a perspective view showing the several parts of the improved device in disassembled relation.

Referring first to Figs. 1 and 2 of the

drawings, I have herein shown a conventional type of drum-winding machine for winding packages of yarn or thread with the strands laid in helical coils thereon. As illustrated in these views, 2 designates the cylindrical drive-roll or friction-drum which drives the mandrel or cone-holder 3 through peripheral contact therewith. The mandrel or cone-holder 3 rests against the surface of the drum 2 at the start of the winding and the yarn, thread or other attenuated material ⁵⁵ ₆₀ ₆₅ ₇₀ ₇₅ ₈₀ ₈₅ ₉₀ ₉₅ ₁₀₀ ₁₀₅ ₁₁₀ ₁₁₅ ₁₂₀ ₁₂₅ across which the yarn draws and the co-operating upper blade 16 having a similar straight edge 21 arranged in parallel spaced relation thereto. The main blade 15 is formed with a rectangular arm or guide 22 extending upwardly from its base or foot 17 and provided with a substantially V-shaped groove 23 on its rearward face extending parallel with and adjacent its side. 10 The blade 16 is constructed in the form of a rectangular strip bent or folded around at its end in the loop-portion 24 which is adapted to enclose the upright arm or guide 22 on the blade 15. The rearward folded portion of the loop 24 is bent inwardly at its end to provide a key or spline 26, the forward edge of which is adapted to engage and slide in the groove 23 on the back of the arm 22. It will be noted from Figs. 4 and 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

of the blade 16. A washer 38 is then applied to the stud 33 with the end of the latter riveted thereover at 39 as shown in Fig. 4. The riveting of the stud at its rearward end draws its head snugly against the forward part of the loop 24 on the blade 16 with the eccentric hub or boss 36 received in and engaging the sides of the slot 30. The blade 16 will thus be secured firmly in place on the upright arm 22 of the blade 15 with its spline or key 26 engaging the vertical groove 23. Due to the spring tendency of the loop 24 the key 26 engages the groove 23 with a slight friction so as to prevent play between the parts and also to provide a slight resistance to the sliding movement of the blade 16 on the blade 15.

When it is desired to adjust the width of the slot or opening 27 between the cooperating edges 20 and 21 of the blades 15 and 16 a suitable key or wrench is inserted in the hole 35 in the head 34 of the stud 33 to turn the latter. Rotation of the stud 33 will cause its eccentric hub or boss 36 to act on the sides of the slot 30 to slide the blade 16 upwardly or downwardly on the arm 22 in accordance with the direction in which the stud is turned. The eccentricity of the hub or boss 36 is relatively slight so that the stud 33 must be turned to a considerable degree to adjust the blade 16 to a very slight extent. That is to say, the arrangement of the adjusting means is such that a very fine adjustment may be secured so that the width of the slot 27 can be varied within precise limits and with great accuracy in accordance with the size or thickness of the yarn to be operated upon.

Another advantage of the improved adjusting-means results from the arrangement whereby the stud 33 can only be turned with a wrench or key adapted especially to fit the hole 35. With slab-catchers of the ordinary type, where adjustment is made by turning a screw or bolt, the device may be tampered with by unauthorized persons. It is often the case where operatives are working on piecework and required to break out knots and slubs to improve the quality of the yarn, that in order to prevent frequent stoppages in the winding or other process they will open the slab-catcher to let some of the knots and slubs pass through. With the present improved device, after the slab-catcher has been once adjusted in accordance with the size of yarn being operated upon the operator is prevented from tampering with the adjustment which can only be changed by the overseer or other authorized person having possession of the special key or wrench.

When the present improved device is applied to use in the manner shown in Figs. 1 and 2 of the present drawings the yarn or thread *y* is drawn up from its source of supply (not herein illustrated), led through

the tension-device 5, and thence threaded through the slot 27 in the slab-catcher and led to the thread-guide 4 of the winding machine.

5 As the machine operates to wind the cop or package on the mandrel 3 the yarn is traversed longitudinally thereof, causing it to slide back and forth in the slot or opening 27 of the slab-catcher and thereby tending 10 to clear the slot of lint, fluff, or motes collected on the edges of the blades 15 and 16. It is to be understood, however, that my present improved device may be used in other positions than that herein shown and 15 also applied to other types of textile machines or apparatus, the present showing being by way of example only.

It will be observed that the present improved slab-catcher is extremely simple in 20 construction and arrangement as comprising substantially only three parts, the two adjustable blades and the adjusting-means or stud which operates the movable blade. The main parts of the device may be constructed in the form of sheet-metal stampings to provide for economical manufacture, and the coordination of the parts is especially designed to prevent derangement or getting out of order.

30 While I have herein shown and described a preferred embodiment of the improved device it is to be understood that various modifications may be made in the form and arrangement of its parts without departing from the spirit or scope of the invention. Therefore, without limiting myself in this respect,

I claim:

1. In a device of the type specified, the 40 combination of a pair of blades arranged with their edges in opposite spaced relation to provide an opening therebetween through which the yarn draws, means for adjusting the relative position of said blades to vary the width of the opening, and resilient means integral with one blade and engaging the other blade to frictionally resist the adjustment between the blades.

2. In a device of the type specified, the 50 combination of a blade-member, a second blade-member arranged opposite the first member with an opening therebetween through which the yarn draws, one of said members being movable with respect to the other to adjust the width of the opening in accordance with the size or thickness of the yarn, resilient means for frictionally resisting the relative movement of the members, and an eccentric adapted for rotation to adjust said members to vary the width of the opening therebetween.

3. In a device of the type specified, the 60 combination of a fixed element, a movable element arranged in spaced relation thereto to provide an opening through which the

yarn draws and formed with a slot, a manually-rotatable stud having an eccentric portion engaging the slot in the movable element to adapt it to adjust the latter in position to vary the width of the opening between the elements, and resilient means frictionally engaging between the blades to resist the adjustment of the movable blade.

4. In a device of the type specified, the 70 combination of a fixed blade, a second blade arranged with its edge in spaced relation to that of the fixed blade and slidable with respect thereto, a rotatable stud having an eccentric portion engaging the slidable blade to adjust the latter toward and away from the fixed blade to vary the width of the opening therebetween, and resilient means frictionally engaging between the blades to maintain the slidable blade with 80 its edge in parallel relation with that of the fixed blade.

5. In a device of the type specified, the 85 combination of a relatively fixed blade, a second blade slidable on the fixed blade, one of said blades provided with a groove, resilient means on the other blade engaging the groove to maintain the edges of the blades in parallel spaced relation during the movement of the slidable blade, and a rotatable stud having an eccentric hub engaging 90 the slidable blade to adjust the latter to vary the width of the space between the blades.

6. A device of the type specified comprising a pair of blades, one of said blades provided with an arm, a resilient loop on the 100 other blade enclosing the arm on the first blade to adapt it to slide thereon and acting frictionally thereagainst to resist the sliding movement, and means acting between the loop and the arm to cause a relative sliding movement between the blades to adjust 105 their edges in parallel spaced relation.

7. In a device of the type specified, the 110 combination of a relatively fixed blade formed with a projecting arm having a groove therein, a movable blade having a resilient looped portion enclosing the arm on the fixed blade and provided with a spline at its end frictionally engaging the groove therein to resist the movement of the movable blade, and means for sliding the movable blade on the fixed blade to adjust the width of the opening between their edges.

8. In a device of the type specified, the 115 combination of a fixed blade formed with a straight edge across which the yarn draws and provided with an arm extending perpendicularly thereto, a movable blade provided with a straight edge adapted to be maintained in spaced relation with the corresponding edge of the fixed blade and formed with a loop enclosing the arm on the fixed blade to adapt it to slide thereon, a slot in the side of said loop, and a stud journalled in the arm of the fixed blade and 120 125 130

provided with an eccentric portion engaging the slot in the loop of the movable blade to adapt it to slide the latter to adjust the width of the opening between the edges of the blades.

9. In a device of the type specified, the combination of a fixed blade having an edge across which the yarn draws and a guiding portion extending at right-angles thereto and formed with a groove, a movable blade having an edge adapted to be held in spaced relation with the edge of the fixed blade and provided with a loop portion enclosing the guide on the fixed blade with a spline at the end of the loop engaging the groove in the guide, said loop exerting a spring tension to maintain the spline in frictional engagement with the groove in the guide, and means to adjust the movable blade on the fixed blade to vary the width of the opening between their edges.

10. In a device of the type specified, the combination of a pair of blades arranged with their edges in parallel spaced relation to provide an opening through which the yarn draws, one of said blades formed with a slot extending at right-angles to its edge and the other blade provided with a resilient loop straddling the sides of the fixed blade and formed with a right-angled portion at its end adapted to frictionally engage the groove in the opposite blade, and means for

effecting a relative sliding movement between the blades to adjust the width of the opening between their edges.

35

11. In a device of the type specified, the combination of a relatively fixed blade formed with an edge across which the yarn draws and having a groove in its face extending at right-angles to said edge, a second blade having a portion folded to straddle the sides of the fixed blade and formed with a spline engaging the groove in the fixed blade, and a stud journalled in the fixed blade and projecting through the folded portion of the slideable blade, said stud formed with an eccentric portion adapted to act on the slideable blade to vary the width of the opening between their edges.

40

12. In a device of the type specified, the combination of a blade formed with an offset foot for attaching it in fixed position and provided with a guide arm having a groove in its side, a fixed blade provided with a looped portion enclosing the guide arm on the fixed blade and having a spline at its end engaging the groove therein, and a stud journalled in the arm of the fixed blade and formed with an eccentric engaging with the movable blade to slide the latter to adjust the width of the opening between the blades.
